BAG CLOSURE

Philip S. Coghill, Wilmington, Del., assignor to
 E. I. du Pont de Nemours & Company, Wil-
 mington, Del., a corporation of Delaware

Application January 15, 1942, Serial No. 426,863

1 Claim. (Cl. 93—35)

This invention relates to packages, especially the closing and opening of bags and like containers. More particularly it appertains to devices to be associated with the end sections of bags made of transparent regenerated cellulose film and the like, for securely closing and facilitating the easy opening and dispensing of the contents thereof.

The primary object of this invention was to improve bag closing, opening and dispensing arrangements. Other objects were to provide for the easy opening, without destruction or weakening, of bags; to provide pouring spouts for powdered products and other free-flowing products; to close bags containing powdered and other free-flowing materials in a leak-proof manner by inexpensive and easily applied means; and to provide for adequate reclosure of the opened bags. Still further objects were to provide tabs or sections simulating tabs, adapted to provide pouring apertures; to provide a cut opening in a bag closure; to prevent, by providing reenforcement, the tearing or splitting of bags after a cut opening has been made, and to provide a device which reinforces a bag closure in such a way that the said closure can be cut to form a pouring opening without weakening the bag.

Yet a further object was to provide a device which reenforces a sealed bag mouth closure in such a way that the said closure can be torn apart with the fingers to form a pouring spout without weakening the bag, and without complete opening of the bag mouth. A general advance in the art, and other objects which will appear hereinafter, are also contemplated.

It has now been found that enclosing within or associating in a related manner with, the mouth of a bag with a simple blank described in detail hereinafter, overcomes the common objections heretofore encountered when flowable products such as beans, flour, sugar, rice and the like were packaged in transparent wraps. The present invention provides an improved bag and related container opening arrangement which permits easy opening, allows the contents to be dispensed in a controlled stream, can be adequately reclosed, and forestalls wrapper splitting and untimely spills and leakage of flowable products packed in clear sheeting.

How the foregoing objects and related ends are accomplished will be apparent from the following exposition in which are disclosed the principle and divers embodiments of the invention, including the best mode contemplated for carrying out the same. The written description is

amplified by the accompanying drawings, in which:

Figure 1 is a perspective view of a bag with its mouth folded together and sealed with a closure device of this invention;

Figure 2 is a top plan view of the closed and sealed bag mouth illustrated in Figure 1;

Figure 3 is a fragmentary perspective view similar to Figure 1, showing the folding of the bag mouth preliminary to its association with the closure device;

Figure 4 is a plan view of the blank illustrated in Figure 1;

Figure 5 is a perspective view of a bag with its mouth pressed together and fastened with a modified form of closure device of this invention;

Figure 6 is a plan view of the blank illustrated in Figure 5;

Figure 7 is a perspective view of a bag with its mouth pressed together and fastened with another modification of the closure device of this invention;

Figure 8 is a plan view of the closure device of Figure 7;

Figure 9 is a sectional plan view taken along the line 9—9 of Figure 7;

Figure 10 is a perspective view of a bag with its mouth pressed together and secured with still another modification of the closure device of this invention;

Figure 11 is a plan view of the blank shown in Figure 10;

Figure 12 is a perspective view of a bag with its mouth pressed together and sealed with a modified form of the closure device of this invention;

Figure 13 is a plan view of the blank shown in Figure 12;

Figure 14 is a top plan view of the bag and closure illustrated in Figure 12;

Figure 15 is a perspective view of a bag with its mouth pressed together and sealed with yet another modified form of the closure device of this invention;

Figure 16 is a fragmentary perspective view showing an intermediate step in the closing of the bag illustrated in Figure 15;

Figure 17 is a plan view of a modified form of the closure blank shown in Figures 15 and 16;

Figure 18 is a plan view of the closure blank shown in Figure 15;

Figure 19 is a plan view of the bag and closure device of Figure 15;

Figure 20 is a perspective view of a bag with its mouth pressed together and sealed with a

closure device which is a modification of the closure device of Figure 18;

Figure 21 is a plan view of the mouth of the bag shown in Figure 20;

Figure 22 is a perspective view similar to that shown in Figure 20, but with a portion of the closure device removed to form a pouring spout; and

Figure 23 is a plan view of the closure device shown in Figure 20.

The facility with which the various types of bags (for example, flat, mandrel, satchel, spiral, square, automatic) can be formed from cast regenerated cellulose film, and the tremendous sales appeal of commodities packed therein, has, as is commonly known, greatly extended the use of this sheet material in this field. Unfortunately, regenerated cellulose sheet tears very readily once a break has been made, and this has militated against its use in forming containers for materials which must be dispensed in small portions over considerable periods of time. Heretofore no really satisfactory method of keeping a regenerated cellulose bag intact, after its mouth had been cut or broken to facilitate dispensing its contents, has been known. The present invention overcomes these difficulties in a simple and inexpensive manner.

Referring now to page 1 of the drawings, comprising Figures 1, 2, 3 and 4, there is illustrated at 4 a paper blank or form, comprising sections 30, 40, 50, 60, 70 and 80, bounded by the edges of the blank, printed lines 34, 56 and 78 or folding lines 35, 46, 58 and 87. It will be noted that one end of the line 78 is at the scored line 58, and that the other end does not quite extend to the edge 87. In closing a bag with this blank, the blank is folded along line 58, the tab comprising sections 30 and 40 folded along the line 35—46 to overlie the edge 87, this tab sealed to 40 the underlying portions of sections 70 and 80, and the resultant positioned over the mouth of the bag and heat sealed thereto.

Triangular portions 24 of the bag mouth are folded downwardly, for example, as shown in Figure 3, to better fit the bag to receive a closure device. In a preferred mode of operation the assemblage comprising the bag with the folded mouth and the folded blank thereover is subjected to a heat sealing operation by being pressed between corrugated heat sealing irons, whereby the bag and closure are firmly secured together and the sealing operation completed. The neat appearance of the closure will be obvious from the plan view of the same in Figure 2.

To open the bag, and incidentally provide a pouring spout, the closure device is severed along the lines 34, 56 and 78. This can be accomplished by tearing, or by snipping with a pair of scissors or other convenient instrument. As will be apparent from Figure 1, the construction enables an adequate reclosing of the bag to be opened, by merely pressing the sides of the aforementioned pouring spout back into the position which they occupied before the bag was opened.

The bags to which this type of closure is applied are ordinarily made of plain regenerated cellulose sheet, which material, though well known in the art, is for the sake of convenience described in detail elsewhere in the specification. The blank 4 is treated on one side (the side that contacts the bag) so that it seals to the bag material during the heat sealing operation. In U. S. A. Patent 2,174,885 of October 3, 1939, there is disclosed a resinous heat sealable

coating which is typical of the materials that may be employed for this purpose. A gummed surface is the expedient preferably employed to bring about the heat sealability. The blank is preferably of a character which can be readily torn with the fingers, for example, a 50 to 60 pound stock.

Modified forms of the previously described closure arrangement, in which the closure blanks 10 are designed to be positioned within the bag mouth, are illustrated on page 2 of the drawings, comprising Figures 5 through 9. In these cases the bag is made of a heat sealable material, preferably regenerated cellulose sheet having a heat sealable moistureproofing coating. Although such material is in common and extensive use, details of its preparation are set forth hereinafter.

In Figure 6 there is illustrated a closure blank 20 comprising sections 101, 103, 104, 106, 108 and 110, delineated by printed lines 102 and 105, scored line 109 and line 107 indicating one edge of a glue strip, and the edges of the blank. Because of the economies of production, the glue strip is continuous along the edge 111, but only 25 half of such a strip, that consisting of sections 104 and 106, is shown because the remainder is functionally unnecessary. In employing the closure device illustrated in Figures 5 and 6, the blank is folded along the line 109 and sealed along the edge 111 by means of the adhesive on the sections 104 and 106, together with the adhesive (if any) on the portions of sections 101 and 103 which sections 104 and 106 contact. The 30 resulting triangularly shaped form is then positioned within the mouth of the bag, the sides of the bag mouth pressed thereagainst, and the assemblage pressed between the jaws of a conventional heat sealing device. The surface of the blank 6 opposite that containing the adhesive material along the edge 111, ordinarily has a smooth clay coating to enable the blank to be heat sealed to the bag material. Preferably the blank is constructed of 50 to 60 pound stock or other paper which can be readily torn with the fingers. Any coating which will securely seal to the bag material, when activated by heat, may be used.

To open the bag, the blank is cut or torn along 35 the line 102. Since the under side (inside) of the blank does not heat seal to itself, access through the heat sealed section along the bag mouth is provided. It will be appreciated that the bag material is heat sealable to itself, so that 40 the seal extends completely across the mouth of the bag, whether or not the bag walls are separated by the material of the blank 6.

A modification of this type of blank, in which the folded blank completely fills, or extends completely across, the inside of the bag mouth, is shown at 8 in Figure 8. This blank comprises, 45 similarly to blank 6, sections 121, 123, 124, 126, 128 and 130, delineated by the edges of the blank, printed guide lines 122 and 125, scored line 129, and lines 127 and 131 representing the edge of an adhesive strip. As was the case with the blank 6, the adhesive section extending along the edge 132 may continue along the entire side of the blank, but in the interest of clarity only the portion necessary for satisfactory functioning of the closure blank is shown in the drawings. This blank is employed in somewhat the same manner as the blank 6, that is to say, it is folded along the line 129, and the overlapped portions along 50 the edge 132 sealed.

The bag illustrated in Figure 7 has side gussets, and in the preferred mode of operation these gussets extend up between the sections 121 and 128, as is quite clearly shown in the sectional view in Figure 9. The inside surfaces 133 and 134 of the thus positioned blank, like the corresponding surfaces of the blank 6, do not heat seal to themselves, so that when the assembled bag and closure blank are subjected to the heat sealing operation, a satisfactory closure of the bag is obtained, but an opening for dispensing the contents of the bag is available when the blank 8 is torn or cut, for example, along the guide line 122. The inside of the blank should be treated so that even though it does not heat seal to itself, it does heat seal to the bag material. Conventional clay coating satisfactorily accomplishes this purpose. Adequate reclosure of the bag shown in Figures 5 and 7 is obtained by simply pressing the bag mouth and closure device back into flat position.

Closure blanks related to those of Figures 6 and 8 are illustrated in the modifications of the present invention shown on page 3 of the drawings, comprising Figures 10, 11, 12, 13 and 14. In Figure 11 there is shown a blank 11 comprising sections 141 and 143 separated by guide line 142, which make up one-half or one side of the blank, and sections 146 and 148 separated by printed line 153, constituting the other side of the form. Narrow strips of adhesive 147 and 149, along the edges 154 and 155, extend inwardly to the lines 145 and 152, respectively. These strips of adhesive are applied by printing or equivalent means well known in the art. The adhesive, as was the case with the blanks 6 and 8, is preferably of the aqueous type, for example, glue.

The application of this blank 11 is believed to be obvious from a consideration of Figure 10. There the blank is folded along the scored line 144. The portions along the edges 154 and 155 are sealed to the corresponding portions of the other side of the blank, the resultant placed in the mouth of the bag at 19, and the assemblage subjected to a heat sealing operation. Opening the form of pouring spout and reclosing of the resultant package, is secured in the manner previously described.

Although the advantages of a pouring spout formed from the blank 11, which is made up of trapezoidal sections, to the consumer is obvious, it may, in some instances, be more important to consider the economic aspects and for this reason a simpler and more easily prepared blank is illustrated in the modification 13 in Figure 13. The arrangement of this blank is similar to that of Figure 11, since it comprises a central scored folding line 164, having on one side sections 161 and 163, separated by the printed line 162, which serves as a guide in opening, and on the other side sections 168 and 173 separated by the guide line 166. Since blanks of this character are sections cut from continuous narrow paper strips, it is more economical to apply the adhesive sections 167 and 170 continuously along the edges as the blank material moves through the manufacturing or forming apparatus. The lines 169 and 174 indicate the inward boundary, and the edges 172 and 165 the opposite edges of the gum or glue surface portions.

The manner in which this blank is employed is believed clear from a consideration of the bag 15 in Figure 12, and the plan view of the same in Figure 14. It will be understood that it is only necessary for the adhesive sections 167 and

170 to extend along the edges of one-half the blank 13, in order to secure an operative device. If such sections terminated on one side of the line 164, a more expensive mode of application, for example, printing, would be necessary.

One interesting advantage of this blank is that it can be proportioned so that pre-assembly (folding and edge sealing) is not necessary. If the closure blank extends such a short distance 10 above the mouth of the bag that it is encompassed by the jaws of the heat sealing apparatus, the adhesive material may be of a heat sealable character, the edges of the blank sealed to each other, and the blank itself sealed in the bag mouth in one operation. In this type of operation, the blank will normally be supplied to the packager in the flat form shown in Figure 13. It will be appreciated that the blanks of 15 Figures 4, 6, 8 and 11 could also be supplied to the packager in an unfolded condition, but that it is generally preferable to prefabricate, that is, to fold and seal these other types, in the interest of uniformity of production and accuracy of folding.

How much the blank 13 extends outside the heat sealing surfaces, or mouth of the bag, will 20 obviously depend upon the amount of material which the packager wishes to have available for printing (advertising) and consumer manipulation in forming the pouring spout.

On page 4 of the drawings, modifications of the present closure device, in which the blank is assembled partly inside and partly outside the bag mouth, are shown in Figures 15 through 19.

The blank 18, first to be considered, is shown 25 in Figure 18 as comprising sections 201, 203, 205, 207, 209, 211 and 213, bounded by the edges of the blank, scored folding lines 202, 208 and 214, printed tear line 206—210, cuts 204 and 212, and 30 line 208 indicating the edge of an adhesive strip. In using this blank it is folded along the lines 214 and 208 and positioned inside the bag mouth as shown in Figure 16. Thereafter the sides of the bag mouth are pressed together, and the section 203 folded over the mouth of the bag into 35 contact with the outside of the bag, as shown on a somewhat exaggerated scale in Figure 19. This assemblage is then pressed in a heat sealing device to produce the closed bag shown at 6a and 40 b in Figure 15. The folding along lines 214 and 208 may be carried out by the manufacturer as a prefabrication step, or left to the user of the bag to be folded at an appropriate time in the bag closing operation. The under sides of the 45 sections 209 and 211 are coated with an adhesive, and when the folding along the line 208 takes place, the adhesive is brought into contact with the outside surface of the section 205. In order to decrease the cost of manufacture, 50 the adhesive strip may continue past the cut 212 all the way along the edge of the section 213. This follows because such a strip can be applied by passing the edge of the blank along an adhesive-applying roller. The arrangement shown 55 in Figure 18 would normally have to be applied by a printing process. Any more adhesive than that shown in this figure is functionally unnecessary.

The bag is opened and a pouring spout formed 60 by severing the sections 205 and 207, preferably along the lines 206 and 210, from that portion of the blank sealed about the bag mouth.

A closely related modification is illustrated by the blank 17 in Figure 17. This blank comprises 65 sections 181, 183, 185, 188, 193, 194, 191 and

195. The boundaries of these sections are indicated by scored folding lines 182 and 187, printed or scored severance line 92, cut 184, lines 189 and 190 representing the edges of an adhesive section, and lines 186 and 196 indicating the edges of the sealed portion when the blank is folded about the line 187. This blank is employed in a manner generally similar to the blank 18, but the adhesive sections 188 and 191 contact the under side of the section 185. This arrangement is less satisfactory than that in the blank 18 because of the possibility of some of the glue being squeezed into the pouring spout area, and the greater strength obtainable by the outside seal. On the other hand, the blank 18 requires an extra folding operation along the line 208 to bring the adhesive flap on the outside. Such an operation is extremely difficult to perform by automatic equipment, and the user must therefore balance the advantages and disadvantages of the two plans. As was the case with the blank 18, the adhesive section may extend all the way along the long edge of section 195 in order to secure a cheaper mode of adhesive application. It is contemplated that these closures will be prefabricated and presealed by the manufacturer, but they can be shipped unfolded and unsealed to permit the folding operation to be carried out by the packer. By using very wide jaw crimpers in the bag closing operation the seal along the edges of the spout sections may be formed simultaneously. In this case a heat activated adhesive would be necessary.

On page 5 of the drawings, including Figures 20, 21, 22 and 23, a similar blank, designed to be placed on the outside of the closed mouth of a bag constructed of non-heat sealing material, is illustrated. This blank 23 comprises sections 221, 223, 225, 227, 229, 231, 233 and 234, defined by scored lines 222, 224 and 228, cut 226, notch 236, a tear or cutting line indicated at 232 and 235, the edges of adhesive strips indicated at 224 and 230, and the edges of the blank or form. This blank is especially adapted for prefabrication, as will be apparent from a top plan view of the folded blank constituting Figure 21, and the perspective views of the closed and thereafter opened bag closure device illustrated in Figures 20 and 22, respectively.

In applying this closure to a bag mouth, the mouth is closed, pressed flat, inserted in the folded blank, and the resulting assembly pressed between the jaws of a heat sealing device. The surface of the blank which comes into contact with the bag material, is treated or coated with a heat sensitive adhesive, so that adequate adherence to the bag mouth is obtained. The bag 6c is opened in the manner previously described. The sections 231 and 233 are sealed to the outside of the sections 221 and 227 after folding about the line 228 in the manner described in connection with the blank 18. The section 225 is also secured by its adhesive contacting the outside of the section 221. As was the case with the previously described closure forms, the adhesive on sections 231 and 233 may continue past the notch 236 down along the edge of section 234 to its rounded corner. It will be understood that by properly selecting operating conditions, water sensitive adhesives such as glue and the like may be employed in the prefabrication of the closures 17, 18 and 23.

Preferably the bags utilized in this invention are made of regenerated cellulose sheet such as that prepared by the viscose process according to

U. S. A. Patent No. 1,548,864 (Brandenberger), but other transparent products such as low substituted methyl cellulose, organic solvent soluble ethyl cellulose, cellulose acetate (56% combined acetic acid), rubber hydrochloride, water soluble an insoluble polyvinyl compound film, and the like, may be employed. In the modifications requiring the bag to be of heat sealable material, some of these base sheets, such as regenerated cellulose and low substituted alkyl cellulose may require a coating. The conventional coatings of this type are generally moisture-resistant.

Moisture-resistant sheet wrapping material is well known in the art, and there is no need for further details which could serve no purpose other than to burden this specification. The properties, etc., of such materials are described in the patents relating to their manufacture, typical of which are U. S. A. Patents 1,997,583 (Hitt), 2,046,492 (Snyder), 2,060,906 (Snyder), 2,064,292 (Charch), 2,077,396 (Charch & Hershberger), 2,077,399 (Collins & Larson), 2,077,400 (Collins), 2,079,379 (Mitchell), 2,123,883 (Ellsworth), 2,147,180 (Ubben), 2,159,152 (Hershberger) and 2,209,965 (Finzel).

Since air-tight closures are the desideratum, the invention is especially adaptable to bags of moisture-proof material capable of being heat sealed. Other related sheet material involving paper, metal foil, cloth, and the like, as a base sheet may be used when desired. In those instances where the container material need not be heat sealable, a still wider variety of sheeted products is available, for example, other types of moisture-resistant cellulosic sheet such as those described in U. S. A. Patents 1,737,187 (Charch & Prindle), 2,042,589 (Charch & Hershberger), 2,166,366 (Meigs), 2,201,747 (Staudt) and 2,205,210 (Latour) may be used.

The blank to be used with the bags made of heat sealable material, as indicated above, is of a character which can be readily torn with the fingers, for example, a 50 to 60 pound stock, one side of which has a smooth clay coating to enable the blank to be heat sealed to the bag material, and the other side of which is plain or treated, as may be desired, but which is of such a character that it does not heat seal to itself or the bag material. The heat sealable side of the blank may have a resinous heat sealable (or equivalent) coating, for example, that described in U. S. A. Patent 2,174,885 of October 3, 1939.

When the blank is to be assembled prior to positioning about the bag mouth, the adhesive employed may be of the water soluble type such as glue, or the heat sensitive type, as pointed out at various places in the specification.

For convenience, square type bags have been illustrated in the drawings and described in the preceding portion of the specification. The invention is broader, since in many instances other types of containers, such as mandrel, satchel and flat type bags, and overlaps, may be used in a manner used similar thereto.

The present invention makes bag packages and the like more attractive and useful to consumers, since it obviates the principal disadvantages heretofore encountered. In the past the opening of a securely closed bag usually meant the destroying of the top, with the result that the bag was so weakened that it split, spilling the contents or becoming unserviceable immediately, or within a very short time thereafter. In the present invention either the bag mouth is not mutilated, or else the mutilated portions are se-

surely supported by strongly adhered blank sections, and in any case, the integrity of the container is preserved. As a result, the consumer demand for securely fastened containers which can be easily opened without necessitating the immediate transfer of the unused contents to another receptacle for storage, has been supplied.

As many apparently widely different embodiments of this invention may be made without departing from the spirit and scope thereof, it is to be understood that this invention is not limited to the specific embodiments thereof except as defined in the appended claim.

I claim:

The process of closing bags of heat sealable

material in such a way that a tube for dispensing the contents is formed in the mouth thereof, which comprises folding a blank into at least two superimposed layers, partly inserting the folded blank in the mouth of the bag so that a portion of said folded blank extends above the mouth of the bag, and heat sealing a strip or zone extending entirely across the bag mouth and blank, the said blank having the edges which extend in the general direction of the sides of the bag sealed to each other, and the portion joining said sealed edges above the bag mouth being joined to provide complete closure for the bag.

PHILIP S. COGHILL.
